UNITED STATES PATENT OFFICE.

DOUGLAS E. HAMILTON, OF LAWRENCE, KANSAS.

DESIGN FOR A BULLETIN-BOARD.

SPECIFICATION forming part of Design No. 24,559, dated August 13, 1895.

Application filed June 20, 1895. Serial No. 553,488. Term of patent 7 years.

To all whom it may concern:

Be it known that I, DOUGLAS E. HAMILTON, of Lawrence, Douglas county, Kansas, have invented a new and original design for Street-Corner Bulletin-Boards, of which the following is a full, clear, and exact description, reference being had to the accompanying drawing, forming a part thereof.

My object is to produce a new design for street-corner bulletin-boards, and the leading features of the same are vertical columns surmounted by intersecting arches, a console superposed relative to said intersecting arches, and partitions dividing the space between said columns.

Said design is illustrated by the accompanying drawing, in which—

A designates vertical columns, mounted each upon a base B, and surmounted each by a cap C. The bases of said columns are connected by a cross-piece D, and the caps are connected by a cross-piece E. Said caps and said cross-piece E are surmounted by the intersecting arches F, and the approximately triangular spaces G, inclosed between said arches and said cross-piece E, are ornamented by scroll-work and roundels. Said ornamental figures comprise each a roundel, with scrolls branching to each side and above the same. At opposite sides of the vertical or upward branch, and also vertically above the same, are roundels of comparatively small size. The spaces H

formed between the arches alone are ornamented by trisected leaves and by small roundels. The interlacing arches are surmounted by a console I, so as to form a space J, upon which is to appear the name of the street. Cross-pieces K parallel with the cross-pieces D and E intersect the vertical columns A, so as to form the spaces L and the comparatively long vertical and centrally located space M. At the intersection of the columns and cross-pieces which form the central space M appear ornamental figures in the shape of rosettes N, and at all of the other intersections of the cross-pieces K with the vertical columns A appear ornamental figures in the shape of trefoils O. Upon the space M will appear a street-directory and other information which will attract and interest the public, and upon the space L, surrounding said space M, will appear advertisements.

Having thus described my invention, what I claim as new, and desire to secure by Letters Patent, is—

The design for a bulletin-board, as herein shown and described.

In testimony whereof I affix my signature in presence of two witnesses.

DOUGLAS E. HAMILTON.
